ATTORNEY

UNITED STATES PATENT OFFICE.

PETER CEDARQUIST, OF CHICAGO, ILLINOIS.

CLOTHESLINE CLAMP.

Application filed November 30, 1923. Serial No. 677,816.

To all whom it may concern:

Be it known that I, PETER CEDARQUIST, a citizen of the United States, residing at Chicago, in the county of Cook and State of Illinois, have invented new and useful Improvements in Clothesline Clamps, of which the following is a specification.

This invention relates to new and useful improvements in clamps and more particularly to a clothes line clamp. The main object of the present invention is the provision of a clothes line clamp which can be quickly and readily attached to a supporting post, side of a building or other stationary supporting element and whereby a clothes line or like support can be quickly and readily engaged with the clamp and supported in a taut position.

Another object of the present invention is the provision of a clothes line clamp which may be placed in various positions with respect to its support and at the same time effectively grip a clothes line when positioned between the opposed clamping members.

A further object of my invention is the provision of a clothes line clamp whereby the clothes line to be clamped and supported in a taut position may be quickly and readily arranged in position for gripping engagement by the clamping elements and wherein suitable guiding means is provided to limit the lateral movement of the clothes line to one direction and at the same time limit the movable clamping member in its movements for clamping the line so that the movable clamping member will at all times be in a position for readily engaging the clothes line to clamp the same against the stationary member.

With the above and other objects in view the invention consists in the novel features in construction, the combination and arrangement of parts hereinafter more fully set forth, pointed out in the claims and shown in the accompanying drawings in which:—

Fig. 1 is a front elevation of my improved clothes line clamp.

Fig. 2 is a top plan view.

Fig. 3 is a sectional view on the line 3—3 of Fig. 2.

Referring now more particularly to the drawings wherein various reference characters are used to designate the several parts, the numeral indicates a stationary support

to which my improved clothes line clamp is attached. The main body of the clamp comprises a base plate 2 having extended outwardly therefrom at right angles to the base plate 2 and in alignment with one edge of the said plate, a bracket 3. This bracket 3 which is positioned intermediate the ends of the plate 2, is provided with inwardly extending spaced arms 4 which are preferably spaced from the base plate 2 as shown in Fig. 2 and provided at their lower longitudinal edges with the curved surfaces 5 whereby the clothes line 6 or other member to be secured in position may be readily inserted between the arms and the base plate 2.

The base plate 2 is provided with a plurality of outstanding perforated ears 7 through which screws or similar fastening members are passed, for engagement with the stationary support 1 to securely position the clamp with respect to the support. The outer face of the base plate 2 is provided with spaced upstanding flanges 9, the upper longitudinal edges of which are provided with points 10 for gripping engagement with a rope or the like brought into contact therewith. Arranged parallel with the flanges 9 is a second set of flanges 11 arranged in spaced relation and between the flanges 9 as clearly illustrated in Fig. 2. The second set of flanges 11 are each provided with the tapering points 12 positioned with respect to the points 10 whereby the points of the several flanges are disposed in the arc of a circle and in order to securely retain the clothes line in engagement with the points 10 and 12 of the flanges 9 and 11, a movable clamping member 13 is provided. The clamping member 13 includes a handle portion 14 enlarged at its inner end as at 15 and eccentrically mounted for pivotal movement upon the outstanding bracket 3 and positioned between the arms 4 whereby the arms 4 will limit the swinging movement of the clamping member with respect to the gripping points 10 and 12.

The inner end of the clamping member is provided with an angularly disposed engaging portion 16 the outer face of which is arcuately curved as at 17 to conform to the positions of the points 10 and 12 whereby when the rope or line 6 is positioned between the clamping member and the points 10 and 12 the clamping member, when disposed at right angles to the base will force

the line 6 into contact with the points 10 and 12 and prevent any movement on the part of the line 6 in one direction.

- Particular attention is directed to the fact that the clamping member is eccentrically mounted upon the bracket 3 in such a position as to provide for further tightening movement of the line 6 upon movement of the same in one direction, but whereby the 10 clamping member may be readily moved out of engagement with the line upon movement of the line in the opposite direction. Thus when the line is positioned for use and weight applied to the line that portion of the line which is positioned between the gripping points 10 and 12 and the movable clamping member will be tightly gripped between these portions so as to securely retain the line against movement.
- 20 In order to facilitate the movement of the arm 15 an angular finger piece 18 extends out at right angles from the arm 14 whereby the operator may readily grasp the same to manipulate the arm 14 for moving the 25 clamping portion 16 into or out of engagement with the line 6.

From the above description it will be readily apparent that I have provided a simple and improved clothes line clamp which can be readily attached to a stationary support and disposed in either a vertical or horizontal position so that a clothes line may be readily inserted between the gripping points 10 and 12 and the arcuate 30 face of the clamping member for retaining the line in a taut position and further by mounting the movable clamping member in its eccentric position with respect to the bracket 3 the gripping engagement of the 35 clamping members will be governed in accordance with the weight applied to the line.

While I have shown and described the preferred form of my invention I wish it to be understood that various changes and 40 alterations may be carried out during the

manufacture of the same without departing from the spirit of the invention or the scope of the appended claims.

Having thus described my invention what I claim is:—

5 1. A clothes line clamp including a base plate, a bracket extending outwardly from the plate at right angles thereto, arms extending outwardly from each side of the bracket and in spaced relation with the plate, engaging points extending outwardly from the base plate, certain of said points projecting from the plate a distance beyond the ends of the other points, and a movable clamping member carried by the bracket and 55 adapted to be moved into opposed relation with the points for gripping an object placed there between.

2. A clothes line clamp including a base plate, a bracket extending outwardly therefrom, arms carried by the bracket and spaced from the plate, gripping points extending outwardly from the base plate in spaced relation with each other, said gripping points being arranged whereby their outer ends are positioned in the arc of a circle, and an eccentrically mounted clamping member carried by the bracket and adapted 60 for engagement with an article placed between the points and said clamping member.

3. A clothes line clamp including a base plate, a bracket carried thereby, spaced flanges extending from the base plate and of different lengths, engaging points formed at the outer ends of said flanges, the points 65 of said flanges being positioned in the arc of a circle, a clamping member eccentrically mounted upon said bracket and having an arcuate clamping face arranged in opposed relation with the pointed flanges for tightly gripping an object placed between the arcuate 70 face of the clamping member and the pointed flanges.

In testimony whereof I affix my signature.

PETER CEDARQUIST,
